BOTTLE DISPENSER

Alexander Blair and Francis H. Collins, Pittsburgh, Pa.; said Collins assignor to said Blair

Application April 9, 1946, Serial No. 660,762

15 Claims. (Cl. 312—88)

1

This invention relates to dispensers of the coin controlled type for bottles containing liquid refreshment. "Bottles" is used herein in a broad sense to mean any suitable containers, whether made of glass, metal, paper or other materials.

It is among the objects of this invention to provide a coin controlled bottle dispenser of large capacity which permits a customer to select any bottle in the dispenser, but which allows only one bottle to be withdrawn for each coin inserted in the dispenser, and which is easy to refill.

In accordance with this invention a case is provided which is large enough to house several parallel rows of bottles containing different liquids or liquids having different flavors. Means are provided for normally retaining the bottles in the case, but the retaining means can be released by coin controlled means to permit any selected bottle to be withdrawn from the case. While the selected bottle is being withdrawn, the rest of the bottles are automatically locked in the case so that only one bottle can be removed for each coin deposited. Preferably, the bottles are held by their necks by means of separable members, and the selected bottle separates the members engaging it when it is lifted. The separation of the last-mentioned members actuates means which hold the rest of the separable members in bottle-holding position. The separable members may include a single slideable member for each row of bottles, or a series of slides for each row. In the first case the slides cooperate with a stationary member to hold the bottles in the case, while in the second case the slides in each line are adapted to receive the necks of the bottles between their ends which, preferably, are recessed for this purpose. Provision is made for urging the slides in each line toward one another to narrow the spaces between their ends sufficiently to prevent the bottles from being lifted through those spaces. Means are provided for locking the slides in bottle-retaining position. Coin controlled means, which releases the locking means when a coin is inserted, permits a selected bottle to separate the separable members engaging it as the bottle is lifted, and thus permits the bottle to be withdrawn from the case. At the same time the slides of the other lines are maintained in bottle-locking position by means actuated by the separation of the members engaging the particular bottle being withdrawn from the case. Therefore, although a customer may have his choice of any bottle in the case, he can only withdraw a single bottle selected by him, because all of the rest will be

2

locked in the case until another coin is inserted. The tops of the bottles are covered by sliding panels, any one of which may be moved aside to expose a single bottle in one or more lines while all of the rest of the bottles remain covered.

The preferred embodiment of the invention is illustrated in the accompanying drawings in which Fig. 1 is a plan view of our dispenser; Fig. 2 is a similar view with the cover raised; Fig. 3 is a view, with the cover removed for the sake of clearness, showing one of the bottles being withdrawn from the case; Fig. 4 is an end view of the dispenser; Fig. 5 is a transverse section taken on the line V—V of Fig. 1; Fig. 6 is a longitudinal section taken on the line VI—VI of Fig. 2 with the cover down; Fig. 7 is a view, similar to Fig. 3, of a modification of this invention; and Fig. 8 is a vertical section taken on the line VIII—VIII of Fig. 7.

20 Referring to Figs. 1 to 6 of the drawings, a case 1 is provided which is large enough to contain several rows of bottles 2 and the ice which keeps their liquid contents cool. To simplify the drawings, a case is shown that will accommodate 25 only two short rows of bottles, but in practice the case generally is large enough to hold several dozen bottles. The case may be provided with legs or be supported by a table or the like. Extending across the top of the case on both sides 30 of the rows of bottles are rails 3 the sides of which are provided with grooves 4 that support the side edges of lines of slides 6, as shown in Figs. 2, 3, 5 and 6. The ends of the slides preferably are provided with recesses so as to form openings between the slides for receiving the reduced necks 35 of the bottles when the slides are disposed end to end. Movement of the slides toward the left is limited by normally stationary L-shape members 7 (Fig. 6) which are hinged at their lower 40 ends to the end wall of the case and which are provided with vertical openings 8 for receiving pins, to be described later, that hold these members in position. As shown best in Fig. 6, the slide at the opposite end of each line has a block 45 9 attached to its lower surface with a coil spring 11 compressed between the block and the adjacent end of the case in order to urge the slides toward one another. The openings between the slides in which the bottle necks are disposed are 50 smaller, when the slides are together than the lower portions of the bottles, whereby to prevent the bottles from being withdrawn from the case.

The slides at the right hand ends of the lines also carry horizontal wedges 13 which project 55 from their outer ends and from the end of the

case itself. The backs of the wedges preferably are parallel to the back of the case, and their front edges are inclined. In order to lock the slides in their bottle-retaining position, locking members 14 are disposed at the end of the case adjacent the points of the wedges. These members, by blocking movement of the wedges to the right, normally keep the slides from being moved along the rails and separated. The rectangular locking members are mounted in grooves 16 in vertically spaced rails 17 extending across the end of the case, and preferably carry vertical rollers 18 at their ends. All except the rear locking members are slideable along the grooves. The locking members normally are urged rearwardly toward one another by means of a spring 19 compressed between the front member and a conventional coin controlled device 21 attached to the front of rails 17. When together, the adjoining rollers of different locking members are disposed at the points of the wedges, as shown in Fig. 2. The coin controlled device normally keeps the locking members from being moved forward, to prevent the wedges from being moved outwardly between them.

When a coin is dropped in the device 21 it releases the locking members 14 and allows one or more of them, depending on the line from which a bottle is being removed, to be moved forward by the wedge at the end of that line, because the inclined edge of the wedge pushes the adjoining roller 18 forward as the bottle being withdrawn separates the pair of slides engaging it. The locking member or members moved ahead by that wedge block outward movement of any wedge in front of the displaced wedge while at the same time the rear edge of the same wedge prevents any locking members behind it from being moved forward by other wedges. This prevents any other bottles from being withdrawn from the case.

To prevent anyone from holding the wedge that has been moved to the right in its right hand position so that other bottles might be removed from the same line without paying for them, the case is provided with a hinged and locked cover 26. The bottom of this cover is provided with short pins 27 that project into the holes 8 in the L-shape members 7 to hold them in place when the cover is closed, as shown in Fig. 6. When the cover is raised by the service man who wishes to refill the case, members 7 are released from the pins and can be swung outwardly from between the rails as indicated in broken lines in Fig. 6. This allows the slides to be separated so that new bottles can be dropped down between them. The cover has a frame 28 with slots 29 extending across it for receiving the opposite ends of a plurality of sliding panels 31 that form the top of the cover. There is a separate panel above each cross row of bottles, and as shown in Fig. 6, there is a space at the right of the right hand panel only wide enough to receive that panel when it is slid to the right. That space is covered by a stationary panel 32 under which the right hand panel can slide; but normally the sliding panel is pulled to the left by coil springs 33 attached to it and to pins 34 projecting inwardly from the front and back of the frame. The sliding panels therefore are held together so that the bottles will be covered except when one or more of the panels is pushed to the right. As a further precaution against theft of bottles, a plate 36 may be secured to the bottom of the cover frame and be provided with circular openings 37 just large enough to allow the bottles to be lifted through them.

When a customer desires to secure a bottle from this dispenser he drops a coin of the correct denomination in the slot of the coin controlled device 21 to release, in well known manner, the locking members 14. He then slides one or more panels 31 to the right until he uncovers the bottle containing the liquid he wishes to drink, whereupon he grasps the top of the bottle and lifts it from the case. This is permitted because the released locking members 14 permit the slides in any line to be separated by the bottle that it is desired to remove. For example, the second bottle from the right in the front row in Fig. 3 is shown as being lifted between the adjoining pair of slides 6. This has moved the two slides at the right of the bottle toward the right end of the case, and caused the adjoining wedge 13 to be projected between the front pair of rollers 18. The front locking member is moved ahead by the inclined front edge of the wedge to permit this projection of the wedge between the rollers, but the middle locking member is maintained in its original position by the rear edge of the wedge so that no bottle can be removed from the back row. As soon as the bottle has been removed, the displaced slides are snapped back to their original position by the spring 11 in that line, the displaced locking member is retained to operative position by spring 19, and the panels 31 likewise are moved back into covering position by the springs 33 attached to them. Another bottle therefore can not be removed until another coin is dropped in the coin controlled device 21.

In case a bottle is lifted from the rear row instead of the front row, the wedge 13 at the end of that row will be projected between the middle and rear locking members 14, as shown in Fig. 4. The inclined front edge of the wedge will move the middle and front locking members forward to a position in which the other or front wedge will strike against the middle locking member if any attempt is made to move that wedge to the right. Consequently, the front row of slides are locked together when a bottle is being removed from the rear row.

Referring now to the embodiment of the invention illustrated in Figs. 7 and 8, instead of using a line of slides for each row of bottles, a single long slide 41 is employed. The two parallel slides shown are mounted in grooves in rails 3' that extend across the top of the case 1' to which they are secured. Each slide is provided with a series of openings 42 which are large enough to permit the bottles 2', with which the case is stocked, to pass through them. The bottom of the case is provided with a plurality of shallow recesses 43 for receiving the bottoms of the bottles in order to properly position the bottles in the case. One end of each slide carries a wedge 13', like those previously described, which normally is held in its left hand position by locking members 14' slidably mounted across the ends of the slides in grooved rails 17'. In this position the slide engages or is disposed close to the right hand side of the bottle necks, as shown in Fig. 8 and in the back row of Fig. 7.

As the size of openings 42 in the slides can not be changed, additional means must be provided to help lock the bottles in the case. This means, in this embodiment, consists of plate 36' mounted on the bottom of cover frame 28'. The plate openings 37', which are large enough to allow the bottles to pass through them, and are substantially the same size as slide openings 42, are disposed in such position relative to the underlying

slide openings that the plate openings are offset to the right relative to the slide openings so that the plate will engage or be close to the left side of the bottle necks. In other words, the effective size of the passage through two superimposed openings 37' and 42 is reduced to such an extent that the bottle therein can not be lifted through the slide and plate.

In order to remove any desired bottle from the case the necessary coin is dropped in coin controlled device 21', which releases locking members 14'. The selected bottle then is pulled upwardly by its upper end, and this movement causes it to push the adjoining slide to the right until the openings in the slide register with the plate openings above, as shown in the front row in Fig. 7. The bottle, such as the second from the right, can be lifted through the registering openings because they are large enough to pass the largest diameter of the bottle. Although, the other slide and plate openings in the same row register with each other at the same time, no other bottles can be removed from that row because sliding panels 31' cover their upper ends and can not be moved aside while the first bottle is being withdrawn from the case. Also, the wedge 13' carried by the displaced slide prevents, as explained in connection with the first embodiment, the other slide or slides from being moved toward the right to release bottles in any other row.

The dispenser just described is especially easy to refill. All that has to be done is to unlock and lift the cover. The new bottles then can be lowered into the case through the openings in the slide and set in recesses 43. When the cover is replaced, plate openings 37' will be lowered over the bottle necks, and in cooperation with the slides will hold the bottles in the case.

A bottle dispenser constructed in accordance with this invention has, in addition to the advantages of simplicity and dependability, the advantage of allowing a customer to choose any bottle in the case. He does not have to take the bottle that happens to be at the end of any given row, as is the case with dispensers of this character now in use. When a customer knows that he always can select the particular bottle that he prefers, instead of having to take whatever bottle happens to be next in line, he is more likely to make use of the dispenser, thereby increasing sales.

According to the provisions of the patent statutes, we have explained the principle and construction of our invention and have illustrated and described what we now consider to represent its best embodiment. However, we desire to have it understood that, within the scope of the appended claims, the invention may be practiced otherwise than as specifically illustrated and described.

We claim:

1. A dispenser for bottles having reduced necks, comprising a case for housing a plurality of bottles, separable members adapted to hold the bottles in the case by their necks, means normally locking said members in bottle-holding position, coin controlled means for releasing said locking means to permit any selected bottle to separate said separable members engaging it, whereby the selected bottle can be withdrawn from the case, and means actuated by the separation of said last-mentioned members as said selected bottle is withdrawn for holding others of said members in bottle-holding position.

2. A dispenser for bottles having reduced necks, comprising a case for housing parallel rows of said bottles, horizontal separable members in the case for each row of bottles, the members in each row being provided with cooperating openings for receiving the bottle necks, means urging the separable members in each row horizontally in a direction to lock the bottles in said openings, means for locking the slides in their bottle-locking position, coin controlled means for releasing said locking means to permit any selected bottle to separate the separable members engaging it as the bottle is lifted, whereby the bottle can be withdrawn from the case, and means actuated by the separation of said last-mentioned members as said bottle is withdrawn for holding the separable members of any other row in bottle-locking position.

3. A dispenser for bottles having reduced necks, comprising a case for housing a plurality of bottles, separable members adapted to hold the bottles in the case by their necks, means normally locking said members in bottle-holding position, coin controlled means for releasing said locking means to permit any selected bottle to separate said separable members engaging it, whereby the selected bottle can be withdrawn from the case, and means for holding the rest of said separable members in bottle-holding position while the selected bottle is being removed from the case.

4. A dispenser for bottles having reduced necks, comprising a case for housing parallel rows of said bottles, a line of horizontal locking slides in the case for each row of bottles, the slides in each line being adapted to receive the bottle necks between their ends, means urging the slides in each line toward one another to narrow the space between their ends sufficiently to lock the bottles in the case, means for locking the slides in their bottle-locking position, coin controlled means for releasing said locking means to permit a selected bottle to separate the pair of slides engaging it as the bottle is lifted, whereby the bottle can be withdrawn from between said pair of slides, and means actuated by the separation of said pair of slides as said bottle is withdrawn for holding the slides of any other line in bottle-locking position.

5. A dispenser for bottles having reduced necks, comprising a case for housing parallel rows of said bottles, a line of horizontal locking slides in the case for each row of bottles, the ends of the slides in each line being provided with recesses forming openings between the slides for receiving the bottle necks, means urging the slides in each line toward one another to narrow said openings sufficiently to lock the bottles in the case, means for locking the slides in their bottle-locking position, coin controlled means for releasing said locking means to permit a selected bottle to push one of the pair of slides engaging it away from the other as the bottle is lifted, whereby the bottle can be withdrawn from between said pair of slides, and means actuated by said movement of said one slide as said bottle is withdrawn for holding the slides of any other line in bottle-locking position.

6. A dispenser for bottles having reduced necks, comprising a case for housing parallel rows of said bottles, a line of horizontal locking slides in the case for each row of bottles, the slides in each line being adapted to receive the bottle necks between their ends, stationary means engaging the slides at one end of the lines, resilient means at the opposite end of the lines urging the slides in each line toward one another to narrow the space

between their ends sufficiently to lock the bottles in the case, means normally holding the slides against movement away from said stationary means, coin controlled means for releasing said holding means to permit a selected bottle to push one of the pair of slides engaging it in a direction away from said stationary means as the bottle is lifted, whereby the bottle can be withdrawn from between said pair of slides, and means actuated by said movement of said one slide as said bottle is withdrawn for holding the slides of any other line in bottle-locking position.

7. A dispenser for bottles having reduced necks, comprising a case for housing parallel rows of said bottles, a line of horizontal locking slides in the case for each row of bottles, the slides in each line being adapted to receive the bottle necks between their ends, stationary means engaging the slides at one end of the lines, displaceable members at the opposite end of the lines normally holding the slides close enough together to lock the bottles in the case, coin controlled means for releasing said displaceable members to permit a selected bottle to push one of the pair of slides engaging it in a direction away from said stationary means as the bottle is lifted, whereby the bottle can be withdrawn from between said pair of slides, and means actuated by said movement of said one slide as said bottle is withdrawn for maintaining the displaceable member at the end of any other line in operative position to keep the slides in that line in bottle-locking position.

8. A dispenser for bottles having reduced necks, comprising a case for housing parallel rows of said bottles, a line of horizontal locking slides in the case for each row of bottles, the slides in each line being adapted to receive the bottle necks between their ends, stationary means engaging the slides at one end of the lines, a plurality of longitudinally movable locking members extending across the opposite end of the lines for normally holding the slides close enough together to lock the bottles in the case, said members being movable transversely of said lines to release the slides, coin released means for holding said members in operative position, release of said members permitting a selected bottle to push one of the pair of slides engaging it toward said locking members as the bottle is lifted, whereby the bottle can be withdrawn from between said pair of slides, and a retaining member movable by said one slide toward said members for holding a locking member at the end of any other line in operative position as said bottle is withdrawn.

9. A dispenser for bottles having reduced necks, comprising a case for housing parallel rows of said bottles, a line of horizontal locking slides in the case for each row of bottles, the slides in each line being adapted to receive the bottle necks between their ends, stationary means engaging the slides at one end of the lines, a plurality of longitudinally movable locking members extending across the opposite end of the lines for normally holding the slides close enough together to lock the bottles in the case, said members being movable transversely of said lines to release the slides, coin released means for holding said members in operative position, release of said members permitting a selected bottle to push one of the pair of slides engaging it toward said locking members as the bottle is lifted, whereby the bottle can be withdrawn from between said pair of slides, said locking members carrying rollers at their ends, and a wedge at said opposite end of each line adapted to be moved by the slides toward one

of said rollers, said one slide moving the adjacent wedge toward the adjacent roller as said bottle is withdrawn, whereby to hold a locking member at the end of any other line in operative position.

10. A dispenser for bottles having reduced necks, comprising a case for housing parallel rows of said bottles, a line of horizontal locking slides in the case for each row of bottles, the slides in each line being adapted to receive the bottle necks between their ends, stationary means engaging the slides at one end of the lines, wedges at the opposite end of said lines movable lengthwise thereof by said slides, a plurality of longitudinally movable locking members extending across said lines with their ends adjacent the points of said wedges, a spring urging said members toward one another to hold the slides close enough together to lock the bottles in the case, and coin released means for holding said members in bottle-locking position, release of said members permitting a wedge in any line to be pushed past said locking members as a selected bottle in that line is lifted from between a pair of slides, and said movement of said wedge holding a locking member at the end of any other line in operative position as said bottle is withdrawn.

11. A dispenser for bottles having reduced necks, comprising a case for housing parallel rows of said bottles, a plate provided with rows of openings adapted to receive the necks of the bottles, a slide extending along each row of said openings and provided with a row of openings adapted to receive the necks of the bottles and to register with the adjacent row of plate openings, all of said openings being larger than the bottles, means urging the slides lengthwise to lock the bottles in the case, means for locking the slides in their bottle-locking position, coin controlled means for releasing said locking means to permit a selected bottle to push the slide engaging it lengthwise as the bottle is lifted, whereby to cause the openings in the slide to register with the adjacent plate openings, and means actuated by the displaced slide as said bottle is lifted for holding the slide adjacent any other row of plate openings in bottle-locking position.

12. A dispenser for bottles having reduced necks, comprising a case for housing parallel rows of said bottles, a plate provided with rows of openings adapted to receive the necks of the bottles, a slide extending along each row of said openings and provided with a row of openings adapted to receive the necks of the bottles and to register with the adjacent row of plate openings, all of said openings being larger than the bottles, displaceable members at one end of the slides normally holding them with the bottle necks clamped in said openings, coin controlled means for releasing said displaceable members to permit a selected bottle to push the adjoining slide in a direction to cause its openings to register with the adjacent plate openings as the bottle is lifted, and means actuated by said slide as the bottle is lifted for maintaining the displaceable member at the end of any other slide in operative position to keep said other slide in bottle-locking position.

13. A dispenser for bottles having reduced necks, comprising a case for housing a plurality of bottles, separable members adapted to hold the bottles in the case by their necks, means normally locking said members in bottle-holding position, coin controlled means for releasing said locking means to permit any selected bottle to separate

said separable members engaging it, whereby the selected bottle can be withdrawn from the case, and means adapted to lock the rest of the bottles in the case while the selected bottle is being removed, said last-mentioned means including means adapted to cover the rest of the bottles in the row from which the selected bottle is being removed.

14. A dispenser for bottles having reduced necks, comprising a case for housing parallel rows of said bottles, a plate provided with rows of openings adapted to receive the necks of the bottles, a slide extending along each row of said openings and provided with a row of openings adapted to receive the necks of the bottles and to register with the adjacent row of plate openings, all of said openings being larger than the bottles, means urging the slides lengthwise to lock the bottles in the case, means for locking the slides in their bottle-locking position, coin controlled means for releasing said locking means to permit a selected bottle to push the slide engaging it lengthwise as the bottle is lifted, whereby to cause the openings in the slide to register with the adjacent plate openings, means actuated by the displaced slide as said bottle is lifted for holding the remaining slides in bottle-locking positions, and means above the displaced slide adapted to cover all openings therein except the one through which the selected bottle is being lifted.

15. A dispenser for bottles having reduced necks, comprising a case for housing parallel rows of said bottles, a plate provided with rows of openings adapted to receive the necks of the bottles, a slide extending along each row of said

openings and provided with a row of openings adapted to receive the necks of the bottles and to register with the adjacent row of plate openings, all of said openings being larger than the bottles, means urging the slides lengthwise to lock the bottles in the case, a plurality of longitudinally movable locking members extending across one end of the slides for holding them in bottle-locking position, said members being movable transversely of the slides to release the slides, coin released means for holding said members in operative position, release of said members permitting a selected bottle to push the slide engaging it toward said locking members as the bottle is lifted, whereby to cause the openings in the slide to register with the adjacent plate openings, and a wedge at the end of each slide and adapted to be moved thereby toward said locking members, the ends of the locking members being adjacent the points of the wedges, and the displaced slide moving the adjacent wedge between the ends of adjacent locking members as said selected bottle is lifted to thereby hold a locking member at the end of any other slide in operative position.
